ALFRED C. JOHNSON, OF WINTERS, CALIFORNIA, ASSIGNOR TO JAMES H. MCCOLLOUGH,
OF SAN JOSE, CALIFORNIA

ENGINE

Application filed May 16, 1928. Serial No. 278,187.

This invention relates particularly to internal combustion engines for aeroplanes.

It is highly desirable in aeroplane construction that the engine be so constructed and arranged as to be perfectly balanced, and capable of enlargement to meet all possible requirements as to power development with, of course, a minimum amount of dead weight and mechanical complication, and without increasing wind resistance.

It is one object of the present invention to provide an engine of the character indicated so constructed and arranged as to be perfectly balanced without the use of counterweights.

It is another object of the invention to provide an engine of the character indicated wherein the power developed may be applied to the propeller shaft through the medium of a plurality of banks of cylinders without increasing the size of the crank-shaft and connecting rod bearings over the size necessary for use in a single bank engine.

It is still another object of the invention to provide a perfectly balanced radial aeroplane engine capable of operating a single propeller shaft through the medium of a single bank of cylinders, or a plurality of banks of cylinders, each bank consisting of an even number of cylinders concentrically and radially disposed about the propeller shaft, and provided with pistons having gear connections therewith.

It is also an object of the invention to provide an engine of the character indicated wherein a single piece barrel may be utilized for the crank case thereby providing a well formed, strong and relatively light construction in which the several working parts may be assembled through the ends and the minor operating mechanisms brought together in a compact arrangement at the rear of the engine.

It is a further object of the invention to provide a perfectly balanced high speed engine which delivers its power smoothly and with a minimum amount of friction to a propeller running at geared-down ratio.

Finally, it is a particular object of the invention to provide a gear power transmission

wherein the meshing teeth of the driving and driven gears are held in positive forward driving contact at all times.

In the drawings:

Figure 1 is a section through a portion of 55 a single bank, four cylinder, radial engine embodying my invention.

Figure 2 is a transverse cross section through an engine of the type shown in Figure 1.

Figure 3 is a pictorial diagram of a multiple bank radial engine embodying my invention.

Figure 4 is a section on line 4—4 of Figure 3.

Figure 5 is a perspective illustration of the driving connection between each cylinder and the propeller shaft, partly in section and parts broken away.

Referring now more particularly to the 70 drawings, I show at 1 a cylindrical crank case provided with removable end caps as 2 in which is mounted a propeller shaft 3. The shaft 3 has an end portion 4 of reduced diameter mounted thereon as at 5 and projecting through the rear end cap as shown. 75 A gear 6 is mounted on the shaft 3 and it is through this gear that the shaft is driven.

Equally spaced about the case 1 are openings 7 on which are mounted radially arranged cylinders 8 fitted with pistons as 9, the connecting rods showing at 10.

Mounted in bearings 11 within case 1 and adjacent each cylinder 8 is a crank shaft 12, this shaft lying parallel with the propeller shaft 3 and adjacent the gear 6 thereon. The crank shaft 12 has gear teeth 13 formed thereon to mesh with the teeth on gear 6. An annular shoulder 14 is formed on the shaft 12 in the plane of one end of gear 13, 90 and on this shoulder is formed an annular groove 15 concentrically arranged relative to the shaft 12. At spaced intervals in the length of this groove are formed sockets as 16 in which are seated pins as 17, these pins of course being concentrically arranged relative to shaft 12 and lying parallel therewith. At 18 I show a collar mounted on the reduced portion of shaft 12 to rotate therewith and yet being capable of a rotary movement rela- 100

tive thereto. On this collar are formed gear teeth 19 identical with the teeth 13 as to transverse cross-section and adapted to align therewith but materially shorter than the teeth 13. This collar 18 has an annular groove 20 formed therein in opposed relation to groove 15 and at spaced intervals in the groove 20 are formed sockets as 21 fitted with pins 22, the pins 22 being so positioned as to alternate with the pins 17, and each set of pins 17 and 22 projecting into the opposing groove 20 and 15, whereby to overlap as shown. Inserted in the opposing grooves 20—15 which, when the device is assembled, form a single annular passage, and between each pair of alternating pins 20—17, are springs 23.

The result of this construction is that when the driving gear 13 is rotated in the direction indicated by the arrow the teeth bear against the teeth of the driven gear 6 to rotate the same. But since the gear teeth 19 are only connected to teeth 13 through the medium of the springs 23 it results that they are urged in the opposite direction against the forward surfaces of teeth 6, while the teeth 19 are forced against the rear surfaces of teeth 6.

There is, of course, in all cases a certain clearance between the teeth of the driving and driven gears, and this clearance naturally increases by wear. In the present embodiment of my invention there are four driving gears on the one driven gear, and consequently since these gears are taking the place of fly-wheels, each for its respective crank-shaft, without some controlling means each one of these crankshafts would operate very much the same as an engine with a loose fly-wheel, and this constant knock and vibration would destroy the working parts and result in failure. This would occur through the back-lash of the gears developed in changing from one side of the teeth to the opposing side in different cycles of the engine. The necessary clearance between the teeth would cause destructive vibration in the working parts and as wearing of the gear teeth increased it would naturally progressively approach the point where the engine would be destroyed, and to where the vibration would be projected into the propeller shaft and from it to the propeller hub causing failure of the propeller. By means of the construction disclosed the driving face of the gear teeth is constantly held in positive contact with the drive side of the driven gear teeth so that a smooth rolling motion of the teeth is maintained at all times. To obtain this most desired result the springs need only be depressed a certain amount, they do not have to be balanced. It is only necessary that the aggregate pressure of the springs in each gear set against their respective pins more than balance the mean effec-

tive pressures upon the piston or pistons producing the power which is transmitted through each crankshaft.

The valve assembly 24 in each cylinder is operated by means of rods 25 riding upon cams 26 on shaft portion 5, the weight of the reciprocating parts of each tappet assembly being compensated for by a spring as 27 so that the unbalanced part of the total assembly is reduced to a minimum.

A connection for the propeller is shown at 28. On the rear end plate of the casing 1 are magneto drive shafts as 29 operated by gear connections as 30 to the shaft 5.

In Figures 3 and 4 I show an assembly comprising four banks of cylinders, each bank comprising six radially arranged cylinders. In this arrangement the banks are divided into parts as 31 and 32, and the corresponding cylinders in each pair of banks as 33 are connected to the same crank shaft 12 by means of their respective connecting rods 10. In this arrangement, of course, perfect balancing is achieved in the same manner as set forth in connection with the engine comprising a single bank of four cylinders.

It is to be understood, of course, that while I have herein shown and described certain preferred embodiments of the invention, changes in form, construction, and method of assembly and operation may be made within the scope of the appended claims.

I claim:

1. In combination, a propeller shaft, means for mounting a propeller thereon, an internal combustion engine actuated driving shaft, meshing gears mounted on said shafts, and means inserted between the gears to constantly hold the teeth of the driving gear in positive contact with the teeth of the driven gear with sufficient pressure to counteract all forces acting in a reverse direction between the driving and driven shafts, whereby to obviate the necessity of mounting a fly wheel on the crank shaft.

2. In combination, a driven aeroplane propeller shaft, an internal combustion engine actuated crank shaft having cranks formed thereon, meshing gears mounted on said shafts, and back-lash eliminating means inserted between the gears whereby to obviate the necessity of mounting a flywheel on the said crank shaft.

3. In combination, a driven shaft having an aeroplane propeller mounted thereon, an internal combustion engine actuated crank shaft having not more than two cranks formed thereon and having gear teeth formed thereon as an integral part thereof, a gear mounted on the driven shaft to mesh with the gear teeth on the crank shaft, and back-lash eliminating means inserted between the gears whereby to counteract variable forces traveling in a reverse direction between the shafts

whereby to obviate the necessity of mounting a fly wheel on the crank shaft.

4. In combination with a driven shaft having an aeroplane propeller mounted thereon, a driving shaft, an internal combustion engine connected to the driving shaft and applying non-overlapping impulses thereto to rotate the same in one direction, and meshing gears mounted on said shafts; of back-lash take-up means inserted between the gears whereby to obviate the necessity of mounting a flywheel on the driving shaft by counter-acting the reverse forces acting upon the driving shaft and generated by the non-overlapping impulses.

5. In combination, a driven shaft having an aeroplane propeller mounted thereon and having a gear mounted thereon, an internal combustion engine actuated crank shaft having not more than two cranks formed thereon and having a gear formed thereon as an integral part thereof and meshing with said first mentioned gear, said shaft having an annular shoulder formed thereon in the plane of one end of the second mentioned gear, a collar mounted on the reduced portion of the shaft and seated against said shoulder and rotatable with the shaft and capable of a rotary movement with respect to the shaft, the said collar having gear teeth formed thereon meshing with the first mentioned gear and identical in cross-sectional conformation with the teeth of said second mentioned gear and capable of aligning therewith, and means inserted between the collar and the crank shaft adapted to set up a relative rotary movement between the collar and shaft in opposite directions, whereby to urge the teeth of the driving gear and the collar against opposing faces of the teeth of the driven gear to counteract all forces travelling in a reverse direction between the crank shaft and the driven shaft, and to obviate the necessity of mounting a fly wheel on the crank shaft.

45 ALFRED C. JOHNSON.
